UNITED STATES PATENT OFFICE.

JOHN R. TOWNSEND, OF SOUTH BEND, INDIANA, ASSIGNOR TO GEORGE CUTTER COMPANY, A CORPORATION OF INDIANA.

DESIGN FOR A CANOPY FOR LIGHTING FIXTURES.

Application filed June 27, 1925. Serial No. 13,828. Term of patent 7 years.

To all whom it may concern:

Be it known that I, JOHN R. TOWNSEND, a citizen of the United States, residing at South Bend, in the county of St. Joseph and State of Indiana, have invented a new, original, and ornamental Design for Canopy for Lighting Fixtures, of which the following is a specification, reference being had to the accompanying drawing, constituting a part thereof.

The figure is an elevational view of my new design for a canopy for lighting fixtures.

I claim:

The ornamental design for a canopy for lighting fixtures as shown.

In testimony whereof, I have hereunto subscribed my name this 15th day of June, 1925.

JOHN R. TOWNSEND.
